UNITED STATES PATENT OFFICE.

ANTONIO BONGIOVANNI, OF BARNESBORO, PENNSYLVANIA.

BRUSH.

1,121,788.

Specification of Letters Patent. Patented Dec. 22, 1914.

Application filed June 11, 1914. Serial No. 844,541.

To all whom it may concern:

Be it known that I, ANTONIO BONGIOVANNI, a citizen of the United States, residing at Barnesboro, in the county of Cambria and State of Pennsylvania, have invented 5 a new and useful Brush, of which the following is a specification.

The invention relates to improvements in brushes.

10 The object of the present invention is to improve the construction of brushes and to provide a simple, practical, and efficient brush, of strong and durable construction, designed for the use of barbers for dusting 15 the face and neck to remove cut hair therefrom and to apply powder thereto, and equipped with means for holding a supply of powder and for varying and cutting off the feed of the same.

20 With these and other objects in view the invention consists in the construction and novel combination of parts hereinafter fully described, illustrated in the accompanying drawing, and pointed out in the claims appended hereto, it being understood that 25 various changes in the form, proportion, size and minor details of construction, within the scope of the claims, may be resorted to without departing from the spirit or 30 sacrificing any of the advantages of the invention.

In the drawing:—Figure 1 is a side elevation of a brush constructed in accordance with this invention. Fig. 2 is an enlarged 35 central longitudinal sectional view of the same. Fig. 3 is a transverse sectional view on the line 3—3 of Fig. 2. Fig. 4 is a similar view on the line 4—4 of Fig. 2.

Like numerals of reference designate corresponding parts in all the figures of the drawing.

In the accompanying drawing, in which is illustrated the preferred embodiment of the invention, 1 designates a hollow tubular handle having a removable cap 2 at the upper end and provided with a lower end wall 3 having perforations 4 for the discharge of the contents of the hollow handle. The handle 1, which is designed to be provided with 45 a removable antiseptic lining 5, is provided at its upper end with exterior screw threads 6 and the said cap 2, is interiorly threaded to screw on the hollow handle, and is adapted to be removed to permit powder 50 to be introduced into the said handle. The cap 2 is preferably provided with a hanger

ring 7 linked into an eye 8 of the cap, and adapted to permit the brush to be hung up when not in use. The lower end of the tubular handle is provided with exterior 60 screw threads 9 to engage interior screw threads 10 of a cylindrical valve casing 11, which connects the handle with a cap 12 of a brush head 13.

The valve casing, which is provided at its lower portion 14 with exterior screw threads, screws into an interiorly threaded upper flange 15 of the cap 12, which is also provided with an interiorly threaded lower or outer flange 16. The cap, which is constructed of sheet metal, or other suitable material, tapers inwardly and upwardly from the lower flange 16 to the upper flange 15, and the said lower flange 16 is interiorly threaded to engage exterior 70 threads 17 of the brush head 13. The brush head consists of a disk provided with bristles 18 and having openings 19 for discharging the powder into the bristles to enable the powder to be dusted on a person. 80 The upwardly tapered cap forms a chamber or compartment 20 located above the brush head and adapted to receive powder from the hollow handle and to enable the same to be distributed thereat over the top of the 85 brush head, whereby the powder is distributed more or less uniformly to the brush head.

The cylindrical valve casing is provided at a point intermediate of its upper and 90 lower edges with a transverse partition or diaphragm 21, having an opening 22 and supporting a rotary valve 23, centrally secured to the partition or diaphragm by a rivet 24 or other suitable pivot. The rotary valve or cut off preferably consists of a disk, and it is provided with an opening 95 25 adapted to be carried into and out of register with the opening 22. The valve or cut off, which is adapted to cover and uncover the opening 22, is provided with an outwardly extending handle 26, projecting through a slot 27 in one side of the valve casing 11. The slot 27 limits the movement 100 of the valve or cut off, and it is of sufficient length to enable the valve or cut off to completely cover and uncover the opening 22 of the partition or diaphragm 21. The upper wall of the slot fits snugly against the periphery of the valve or cut off, so that 105 powder is prevented from sifting through the said slot. The threaded connection be- 110

tween the hollow handle and the valve casing enables the handle to be adjusted to arrange the perforated lower end wall 3 different distances from the rotary valve or cut off. This will vary the amount of powder delivered to the chamber 20 at each operation of the valve or cut off. By adjusting the hollow handle to move the lower perforated end wall away from the valve or cut off and the partition or diaphragm, the supply of powder will be increased, and an adjustment of the handle toward the valve or cut off will lessen the amount of powder delivered to the chamber at each operation of the valve. By this construction the desired amount of powder may be delivered to the brush head at each operation of the valve or cut off.

What is claimed is:—

- 20 1. A brush of the class described including a brush head, a hollow handle forming a powder receptacle and provided with a lower end wall having an outlet, and a valve casing connected with the lower end of the hollow handle and with the brush head and provided with a transverse diaphragm having an opening, and a cut off for the said opening, said handle being adjustable to carry its outlet toward and from the cut off to vary the amount of the feed.
- 25 2. A brush of the class described including a brush head, a hollow handle constituting a powder reservoir and provided with a lower end wall having perforations, a valve casing connected with the brush head and provided with a transverse partition having an opening and spaced from the upper end of the valve casing, and a movable cut off mounted on the partition and arranged to cover and uncover the said opening, said valve casing receiving the lower end of the handle within the space above

the partition, and the handle being adjustable toward and from the partition to vary the amount of the feed at each operation of the cut off.

3. A brush of the class described including a brush head provided with a cap forming a chamber, a valve casing extending over the cap and provided with a transverse partition having an opening communicating with the said chamber, said casing being provided at the partition with a slot, a cut off pivotally connected to the partition and arranged to cover and uncover the opening thereof, said cut off being provided with an operating handle extending through the said slot, and a hollow handle constituting a powder receptacle and having a perforated lower end wall, said hollow handle being adjustably connected with the valve casing and movable toward and from the cut off to vary the amount of the feed at each operation of the said cut off.

4. A brush of the class described including a brush head having perforations, a hollow handle forming a powder receptacle and provided with a lower end wall having perforations, a valve casing connected with the lower end of the hollow handle and with the brush head and provided with a transverse partition having an opening and spaced from the brush head to form a chamber to cause a uniform distribution of the powder to the brush, and a cut off for covering and uncovering the opening of the valve casing.

In testimony, that I claim the foregoing as my own, I have hereto affixed my signature in the presence of two witnesses,

ANTONIO BONGIOVANNI.
